Attorneys.

UNITED STATES PATENT OFFICE.

THOMAS J. McCARTHY, OF LOS ANGELES, CALIFORNIA.

PORTABLE JACK.

Application filed June 9, 1924. Serial No. 718,801.

To all whom it may concern:

Be it known that I, THOMAS J. McCARTHY, a citizen of the United States, residing at Los Angeles, in the county of Los Angeles and State of California, have invented new and useful Improvements in Portable Jacks, of which the following is a specification.

This invention consists of the novel features herein shown, described and claimed.

The leading object is to make a jack having a supporting frame mounted on wheels and having a tongue for manipulating the location of the supporting frame, the tongue also being adapted to serve as the jack lever.

Other objects and advantages will appear from the drawings and specification.

The drawings illustrate the details of construction and operation of a portable jack embodying the principles of the invention.

Figure 1 is a top plan view of the portable jack as seen looking downwardly in Fig. 2, as indicated by the arrow 1.

Fig. 2 is a side elevation looking in the direction indicated by the arrow 2 in Fig. 1.

Fig. 3 is a sectional elevation on a plane parallel with Fig. 2 and on the line 3—3 of Fig. 1, and looking in the direction indicated by the arrows, and showing an operation.

Fig. 4 is a view analogous to Fig. 3 and showing a different operation.

Fig. 5 is an enlarged fragmentary detail of the jack dogs shown in Figs. 3 and 4.

The details of construction and operation shown in the drawings are as follows:

The main frame consists of four arms 1 arranged radially and flat. Bearing blocks 2 extend upwardly from the arms 1 and the caster wheels 3 have shanks mounted in the bearing blocks 2. A bearing block 4 extends upwardly from the center of the frame 1 and ribs 5 connect the bearing block 4 to the bearing blocks 2. A housing 6 is formed integral with the arms 1 half way between two bearing blocks 2. A rectangular or square opening 7 is formed vertically through the bearing block 4 and the lifting member 8 is slidably mounted in the opening 7 and has ratchet teeth 9 upon one side. The lifting member 8 is hollow and a flat head 10 has a hollow shank 11 fitting in the upper end of the hollow of the lifting member 8.

A secondary lifting head 12 has a shank 13 fitting in the hollow of the shank 11 and

a supporting flange 14 resting upon the head 10. The secondary head 12 is adapted to be removed and the shank 13 inserted into the opening 15 in the arms 1 out of the way when its use is not desired. The secondary head 12 serves to make the lifting member 8 higher or lower as desired.

The lever prongs 16 and 17 are formed integral with clamping members 18 and 19 and the hand lever and tongue member 20 is inserted between the clamping members 18 and 19 and bolts applied to secure the members together. A supporting dog 21 is placed between the prongs 16 and 17 and a pivot bolt 22 is inserted through the prongs, through the housing and through the holding dog 21 so as to pivotally mount the dog 21 to support the lifting member 8 when the upper end of the dog is in engagement with one of the ratchet teeth 9. So far as the supporting operation is concerned, it is immaterial whether the lever construction is up or down. A lifting dog 23 is mounted between the prongs 16 and 17 upon a pivot 24, the upper end of the dog 23 being adapted to engage a ratchet tooth 9 and raise the lifting member 8 when the handle goes down. Slots are formed through the dogs 21 and 23 below their upper ends and above the pivots, and a leaf spring 25 is mounted in the slots upon pins inserted through the dogs, the tension of the spring being exerted to press the upper ends of the dogs away from each other.

Bifurcated ears 26 and 27 extend downwardly from the dogs 21 and 23 respectively. A slotted link 28 is mounted in the bifurcations of the ears 26 and 27 and pins 29 and 30 extend through the ears 26 and 27 respectively and through the slots in the link 28. An expansive spring 31 is inserted in the slot of the link 28 against the pin 29. A chain 32 is connected to the link 28 and extends through the hollow of the handle member 20 to the bell crank lever 33. A fitting 34 is clamped upon the swinging outer end of the lever member 20 and has a handle 35 offset laterally from the axis of the handle member 20 and has a second handle 36 extending laterally. An eye 37 is attached to a chain 38 and the chain extends through the fitting 34 through the handle member 20 and laterally through the housing 6 and is connected to a pin 39 fixed in the lower end of the lifting member 8.

so that when desired the eye 37 may be pulled to quickly raise the lifting member 8 into engagement with the object to be lifted. The bell crank lever 33 is connected 5 to the handle member 35 by a pin 40.

When it is desired to operate the jack to elevate the lifting member 8, the handle member 35 is grasped in one hand and the bell crank lever 33 grasped with the same 10 hand to pull on the chain 32, thereby pulling on the lower end of the dog 23 to bring the upper end of the dog into engagement with the ratchet teeth 9, then as the handle is moved up and down the lifting member 8 15 will be raised to the desired extent and the dog 21 will hold the lifting member in its elevated position.

The portable jack is intended especially for use around a motor vehicle for raising 20 the axles to remove and replace tires, and so on, and the handle construction, including the member 20, is of considerable length and serves as a tongue so that the lifting and supporting mechanism may be readily 25 run under the vehicle to a desired position. After the supporting mechanism has been properly located a pull on the eye 37 will 30 instantly raise the lifting member 8 into engagement with the axle or other part to be raised and then one or more strokes of the hand lever mechanism up and down will lift the part to the desired extent. If the part is low, as when a tire is flat, the secondary head may be removed and if the parts 35 are of abnormal height the secondary head is used. After the operations have been performed and it is desired to remove the jack, the bell crank lever 33 is released and the handles pressed clear down to the floor or 40 ground and then the dog 23 will contact with the dog 21 and press the dog 21 out of engagement with the teeth 9 and the spring 25 will hold the dog 21 out of engagement, and as the handle is elevated the lifting 45 member 8 will go down a considerable distance, and if this is not sufficient the operation may be repeated.

The operation of lowering the jack given in detail is substantially as follows:

50 It is to be noted that the holding dog 21 has no up and down motion, being swivelled on the pivot bolt 22 on which the handle has a levering operation. The lifting dog 23 moves up and down. These dogs 55 are pressed apart at their upper ends by the spring 25 and are pressed together at their upper ends by the action of the spring 31. This action, however, has a lost motion 60 on account of the pin 30 moving in a slot and functioning to thrust the lower ends of the dogs apart.

As above mentioned when it is desired to lower the jack the hand lever is pressed clear down to the floor into a lower position 65 than shown in Fig. 4, causing the dog 23 to

disengage the dog 21 from the teeth. The dog 21 will thereby be thrust out a considerable distance from the rack 9. The handle is then raised and lowers the jack on the lifting dog 23.

In a certain position of the downward movement the pin 30 moves from the position shown in the slot in Fig. 5 to the other end of the slot and exerts a compressive stress on the spring 31. This forces the 70 holding dog 21 into engagement with the rack. The further upward movement of the handle lowers the lifting dog 23 and the spring 31 exerting a stress to separate the lower ends of the dogs and draws the upper 75 ends of the dogs together, thereby completely disengaging the lifting dog 23 from the rack, the rack being held in this position by the holding dog 21. The handle is then given an idle stroke downwardly which elevates the lifting dog until the reaction of the 80 spring 25 thrusts it into engagement with one of the teeth. When the weight is taken off the holding dog 21 on to the lifting dog 23, the holding dog is forced outwardly as 85 above described and the upward movement of the handle gives a lowering action of the jack. This action may be repeated as many 90 times as is necessary to completely lower the jack.

In the lowering operation it is unnecessary to manipulate the bell crank lever 33. However, it may be actuated if desired to positively force the lifting dog 23 into engagement with the rack in any position.

Especial attention is called to the use of the handle parts 20, 35 and 36 as a tongue for manipulating the lifting and supporting mechanism and as a lever for operating the jack.

When desired, the portable jack may be run under the center of either end of a motor vehicle and operated to lift the end of the vehicle, thereby placing the weight upon the casters of the jack, and then by manipulating the tongue the end of the motor vehicle may be moved laterally at right angles to the running line of the vehicle, and by repeating this operation both ends of the vehicle may be moved laterally to any desired extent.

Various changes may be made without departing from the spirit of the invention as claimed.

I claim:

1. A jack having a supporting frame, a lifting member mounted thereon and having a rack, a lever pivoted on the frame, a pivot therefor, a holding dog pivoted on the same pivot as the lever, a lifting dog pivoted between the said pivot and the rack, a tension device operating with the lever and connected to both dogs whereby both dogs engage the rack when the lever is operated to elevate the lifting member, and means to re-

lease the tension device and disengage the holding dog from the rack to lower the lifting member.

20

2. A jack as claimed in claim 1 in which the tension device comprises a slotted plate, pins on said dogs engaging said slots, and means attached to the lever to draw and release said plate.

25

10 3. A jack as claimed in claim 1 having a spring connecting said dogs to force their teeth away from each other to disengage the holding dog from the rack.

30

15 4. A jack as claimed in claim 1 in which the tension device comprises a slotted plate, pins on said dogs engaging said slots, means attached to the lever to draw and release said plate, and a spring connecting said dogs to force their teeth away from each

other to disengage the holding dog from the rack.

5. In a lifting jack, a supporting frame, a lifting member mounted therein, a lever pivoted to said frame, a pivot therefor, a holding dog mounted on said pivot, a lifting dog pivoted on said lever, extensions on said dogs, pins thereon, a slotted plate engaging said pins, a spring in one slot engaging the pin on the holding dog, a tension means attached to the lever to operate the plate and thereby force both dogs into engagement with the rack, and a spring between both dogs tensioned to normally separate the gripping teeth of the dogs.

In testimony whereof I have signed my name to this specification.

THOMAS J. McCARTHY.
